[57] **CLAIM**

The ornamental design for a fuel injector tester, as shown.

DESCRIPTION

FIG. 1 is perspective view of a fuel injector tester in accordance with my design;

FIG. 2 is a top view thereof;

FIG. 3 is a front view thereof;

FIG. 4 is a left side view thereof;

FIG. 5 is a bottom view thereof;

FIG. 6 is a right side view thereof; and,

FIG. 7 is a rear view thereof.

FIG. 1

FIG. 2

FIG. 3

FIG. 4

FIG. 5

FIG. 6

FIG. 7
